(57) **CLAIM**

The ornamental design for a vehicle exterior, as shown and described.

DESCRIPTION

FIG. 1 is a top, front, and left side perspective view of a vehicle exterior showing our new design;

FIG. 2 is a top, rear, and left side perspective view thereof;

FIG. 3 is a front elevational view thereof;

FIG. 4 is a rear elevational view thereof;

FIG. 5 is a left side elevational view thereof;

FIG. 6 is a right side elevational view thereof; and,

FIG. 7 is a top plan view thereof.

Any broken lines represent an internal boundary of the design; the line itself and the area within form no part of the claim.
